UNITED STATES PATENT OFFICE.

THOMAS MILTON FINLEY, OF ST. LOUIS, MISSOURI.

FLYING MACHINE.

Application filed February 27, 1920. Serial No. 361,361.

To all whom it may concern:

Be it known that THOMAS M. FINLEY, a citizen of the United States, residing at St. Louis, in the county of St. Louis City and State of Missouri, has invented certain new and useful Improvements in Flying Machines, of which the following is a specification.

The invention relates to improvements in flying machines of the Zeppelin type.

The object of the present invention is to improve the construction of flying machines of the Zeppelin type and to provide a practical, efficient and comparatively inexpensive flying machine of this character adapted to lessen the resistance to forward travel or propulsion by arranging the power plants and cabin of the machine much nearer the center of resistance than has heretofore been possible and at the same time by reason of such arrangement to lessen the overhead drag incident to the Zeppelin machine.

Another object of the invention is to provide a flying machine which in settling will offer more resistance than any other machine of this type while in the forward or upward movement will have its resistance reduced to a minimum.

Another object of the invention is to provide a flying machine equipped with interior framework of a strength which will enable it to be constructed much lighter than has heretofore been possible with flying machines of this type, thereby reducing the weight without decreasing the strength.

Another object of the invention is to provide a supporting framework having a central truss or backbone adapted to afford the requisite strength and stability and capable of enabling an exceedingly light framework to be employed at the outer portions for supporting the outer skin or covering.

A further object of the invention is to enable the power plants to be rigidly connected with the interior supporting framework and to permit without injury to the machine the application of the necessary amount of power to overcome the resistance encountered by the machine and propel the latter at the desired speed.

A further object of the invention is to enable the machine by reason of the rigid connection of the power plants with the interior framework to derive all of the advantages or benefits resulting from the gyro-

scopic effect of the propellers without liability of injury to the machine.

The invention also has for its object to provide a machine of this character having sufficient strength to enable it to stand up with its gas bags or containers in a deflated condition whereby the flying machine will be able to sustain and maintain itself firmly on the surface of the ground when desired by the operator.

Furthermore it is the object of the invention to provide a flying machine of the Zeppelin type having sufficient strength internally and externally to enable landing gear to be employed and the machine to effect a landing in a manner similar to the landing of machines of the aeroplane type, that is with the machine landing on the ground heavier than air and held on the ground under its own weight.

A further object of the invention is to enable the machine to be equipped with gas control mechanism for pumping down the gas when the lifting power of the same is not required or it becomes necessary to take care of the expansion without the loss of gas in the ascent of the machine and for returning the pumped down gas to the gas bags or containers of the machine as required, thereby eliminating the necessity for ballast loads that are required on all other machines of this type.

A further object of the invention is to enable all rudder and elevator planes to be so arranged at the rear of the cabin as to leave the body of the machine clear of anything that would increase overhead resistance or strain on the framework of body.

Another object of the invention is to enable the gas control mechanism to be arranged so that the operators will be able to pump down the gas from either end of the machine while leaving the opposite end inflated and also from one side or other of the machine whereby the trim or equilibrium of the machine both longitudinally and transversely may be maintained by the gas control and thereby obviate the necessity of carrying the large elevator planes used on other machines of this type.

Another object of the invention is to provide a flying machine of the Zeppelin type having a body substantially circular in cross-section and tapered at the ends and provided at the bottom with a shallow longitudinal indentation adapted to afford

a descent resisting bottom surface and at the same time enable the cabin and the power plants to extend or be arranged exteriorly of the body and at the same time 5 occupy positions within the actual radius of the body for reducing the resistance and overhead drag of the machine and to enable the power to be applied within the radius of the machine and near the center 10 of the resistance encountered by the machine in the propulsion of the latter.

With these and other objects in view, the 15 invention consists in the construction and novel combination and arrangement of parts hereinafter fully described, illustrated in the accompanying drawings and pointed out in the claims hereto appended, it being understood that various changes in the form, proportion, and minor details of construction within the scope of the claims 20 may be resorted to without departing from the spirit or sacrificing any of the advantages of the invention.

In the drawings, in which like characters 25 of reference designate corresponding parts in the several figures:

Figure 1 is a front elevation of a flying machine constructed in accordance with this invention.

30 Figure 2 is a rear elevation of the same.

Figure 3 is a central longitudinal sectional view of the front portion of the machine.

35 Figure 4 is a similar view of the rear portion of the machine.

Figure 5 is a transverse sectional view of the machine illustrating the construction of the approximately circular transverse frames of the interior framework.

40 Figure 6 is a transverse sectional view through the machine at a point between the transverse frames illustrating the arrangement of the gas bags or containers and the compressed gas sacks or receptacles and 45 their connections with one another and with the compressor.

Figure 7 is a diagrammatic longitudinal sectional view of the front portion of the machine illustrating the arrangement of the 50 gas bags or containers and the gas sacks or receptacles in which the hydrogen gas is compressed, parts being omitted for clearness.

55 Figure 8 is a similar view of the rear portion of the machine.

In the accompanying drawings in which is illustrated one embodiment of the invention the flying machine, which is of the Zeppelin type has a body provided with an 60 outer skin or covering 1 and tapered at its front and rear ends 2 and 3 and substantially circular in cross-section and closely approximating the conventional shape of the body of machines of the Zeppelin type. The body 65 of the machine is provided at the bottom

with a shallow longitudinal indentation 4 extending from the tapered front end of the machine to the tapered rear end of the same and presenting a bottom surface consisting of a substantially flat central portion 5 and inclined side portions 6 extending downwardly and outwardly from the substantially flat intermediate or central portion 5 and preferably curved as shown to present slightly concave portions. By this construction the lower face of the body is slightly concave transversely of the body and is adapted to offer resistance to the downward movement of the body in the descent or settling of the same and increasing the resistance in settling over this type of machines having its body continuously curved and presenting a rounded or convex face at the bottom as in Zeppelin machines of the conventional form. The width of the lower face of the body at the shallow indentation is preferably equal to the length of the radius of the body and the shallow indentation 4 enables power plant casings 7 and a cabin 8 to be arranged exteriorly of the body of the machine at the bottom thereof and substantially within an arc described by the radius of the body. The power plants and the cabin by virtue of this arrangement are brought closer to 90 the center of the body of the machine than the cabins and power plants of other machines of the Zeppelin type and this arrangement reduces the resistance to the forward movement of the machine and also lessens the overhead drag and at the same time enables the power to be applied nearer to the center of resistance than has heretofore been possible with machines of this type.

100 The outer skin or covering 1 which may be of any suitable material is supported by an interior framework preferably constructed of laminated wood but any suitable material either wood or metal or a combination of the same may be employed in the construction of the interior framework. Laminated wood however has been found to possess the requisite strength and is preferred on account of its lightness as compared with metal. The interior framework consists of a central longitudinal truss or backbone 9 and substantially circular transverse frames 10 arranged at intervals and 105 extending outwardly from the longitudinal truss at opposite sides of the same as clearly illustrated in Figure 5 of the drawings. The longitudinal truss or backbone, which extends from the top to the bottom of the body and from one end to the other thereof 110 is provided with tapered front and rear ends 11 and 12 and is preferably composed of vertical and horizontal frame members 13 and 14 and inclined diagonally arranged cables 15 having tensioning devices 16. The 115

tapered end portions 11 and 12 of the longitudinal truss or backbone are provided with marginal frame members 17 and 18 defining the longitudinal taper of the terminal portions of the truss and the extreme ends of the tapered portions are braced by angularly related frame members as indicated at 19 and 20 but the particular construction and arrangement of the frame elements of the longitudinal truss member may of course be varied to suit the requirements and provide a framework of the desired strength. The longitudinal truss has its upper and lower edges or faces located centrally of the body at the top and bottom thereof and interiorly of the same as shown.

The circular or approximately circular transverse frame 10 is composed of vertical and horizontal frame members 21 and 22 and inclined cables 23 provided with tensioning devices 24 and arranged diagonally with relation to the angles formed by the vertical and horizontal frame members 21 and 22. These cables also extend to the marginal portions of the transverse frame at the sides thereof and to the top of the truss and to the top portions of the transverse frame at opposite sides of the truss and are disposed at an angle to each other as shown in Figure 5. The cables are also angularly related at the bottom of the transverse frame and are perfectly balanced and produce uniform transverse tension throughout the frame 10. Frame 10 is also provided with an outer encircling tensioning cable 25 which extends around the substantially circular frame being connected with the vertical and horizontal frame members at the terminals thereof. A transverse frame is also provided with a marginal frame member 26 of circular form extending around the body from one side of the shallow bottom indentation to the opposite side thereof and the terminals of a continuously curved frame member 26 are connected by a bottom arched frame member 27 which defines the outline of the bottom indentation transversely of the body. The encircling marginal tensioning cable 25 is designed to be provided at suitable intervals with tensioning devices 28 and the tensioning devices of the various cables may be of any desired construction. The lower portion of the marginal tensioning cable 25 extends beneath the cabin 8 and assists in bracing and supporting the same.

The cabin which may be of any desired construction extends longitudinally of the machine from the tapered front end to the tapered rear end of the same and it is connected with the framework of the machine and is rigid with and directly supported by the framework and contributes to the strength thereof. The framework of the machine is provided at suitable intervals

with substantially circular ribs 29 consisting of continuously curved portions and arched bottom portions 30 being similar in contour to the marginal frame member or element of the transverse frame. The intermediate ribs 29 which are arranged at suitable intervals for supporting the outer skin or covering of the body are connected with one another and with the transverse frames 10 at the margins thereof by suitable longitudinal frame elements or members 31 which may be of any desired construction and owing to the great strength of the framework of the machine centrally of the body by virtue of the longitudinal truss or backbone and the connection with the cabin thereto an exceedingly light outer cover supporting framework may be advantageously employed. The great interior strength of the framework permits this outer cover or skin supporting framework to be much lighter than the corresponding structure in other machines of this type.

The frame of the machine is provided centrally of the body at the lower portion thereof with a longitudinal passage 32 defined by the side walls 33 parallel throughout the major portion of their length and preferably curved at the top at 34 where they are united with the longitudinal truss or backbone. These walls 33 may be of any suitable laminated wood framework and they preferably coincide with and form continuations of the side walls 35 of the cabin 8 and they provide a structure of increased strength at the lower portion of the central framework of the machine where the power is applied and the greater resistance and strain transmitted. This will afford a strong framework where the power is applied and will enable the requisite amount of power to be used to overcome the resistance encountered by the machine and to propel the machine at the desired speed. A proper support for the application of the necessary power is thus provided and the power plants may be arranged at any desired point along the machine. The power plant casings which are preferably tapered rearwardly to provide a streamline effect are located at opposite sides of the cabin which extends upwardly into the lower portion of the body of the machine so that a portion of the cabin is arranged interiorly and exteriorly of the body and the cabin is thereby enabled to be incorporated firmly and rigidly in the framework of the machine and to constitute a part of a unitary framework or structure. The power plant casings are provided with upwardly extending tubular portions or necks 36 which are secured at their upper ends to the framework of the machine directly above the power plant casings and the said tubular portions 36 communicate with lateral spaces or extensions 37 of the

longitudinal passage 32. The laterally extending spaces 37 are defined by top, side and end walls 38 of laminated wood or other suitable material and they afford passage-
ways from the cabin to the power plant casings and enable access to be readily had to the power plants. The power plants are also connected at the inner sides of the casings with the sides of the cabin by suitable braces 39 and they are also connected by braces 40 and 41 with the framework of the machine, the braces 40 being located at the outer sides of the power plant casings and the braces 41 at the inner sides as clearly shown in Figure 5 of the drawings. The power plant casings will preferably be located at the front and rear ends of the cabin at opposite sides thereof and will be equipped with propellers 42 and 43 but they may be arranged at any other desired points as would be readily understood and the propellers will be tractor and pusher propellers where required.

The flying machine owing to the rigid character of the interior framework and the rigid connection of the cabin and the power plants with the said framework will be equipped at opposite sides of the cabin with landing gear 44 which may be of any desired construction and which will be located at the front, back and at one or more intermediate points. The landing gear which will as shown be connected with the cabin and with the framework of the machine through the power plant casings or other suitable means will provide a suitable base for supporting the flying machine in an upright position and the said landing gear will enable the flying machine to land on the ground in a condition heavier than air so that the weight of the flying machine when the gas is pumped down as herein-after explained will maintain it on the ground under its own weight and without the anchoring or holding means ordinarily required for flying machines of this type.

The main gas bags or containers which are arranged in two sets or series and which are disposed within the body at opposite sides of the longitudinal truss or backbone consists of front and rear end sections or containers 45 and 46 and intermediate sections or containers 47, and the end gas bags or containers are disposed in pairs and are arranged at opposite sides of the longitudinal truss or backbone and within the tapered ends of the body. The intermediate gas bags or containers are located between the transverse frames at opposite sides of the longitudinal truss or backbone and they conform to the configuration of the interior framework at the truss and the walls of the longitudinal passage and also fit the interior of the body at the outer skin or covering at the top, sides and bottom of the

body. The gas bags or containers when fully inflated entirely fill the spaces provided for them at opposite sides of the body which is provided at the bottom with suitable air inlets 48 which permit air to enter the interior of the body between the gas bags or containers and the covering of the body to fill the latter and supply the necessary volume of aeroform fluid within the body to take the place of the gas pumped from the gas bags or containers by the gas control mechanism.

The gas control mechanism which constitutes the subject matter of a separate copending application comprises a compressor 49 preferably located within the upper portion of the passageway and connected by suitable pipes or tubes with the gas bags or containers and also by suitable pipe connections with sacks or receptacles 50 also located within the passageway and adapted to receive the gas pumped down or out of the gas bags or containers located within the body between the passageway and the outer covering. As the machine ascends and the pressure of the atmosphere decreases the gas is pumped down to maintain the proper relation of the gas within the machine and the atmosphere exteriorly of the machine. This will obviate the necessity of permitting the gas to escape and will also avoid carrying ballast loads as the gas from the sacks or receptacles may be returned to the gas bags or containers as the machine descends. Also by the pumping of the gas from the ends of the body or from one end or one side while permitting the other end or side to be inflated the flying machine may be maintained in a trim condition or in equilibrium both longitudinally and transversely and the angle or inclination of the machine may be controlled by means of the gas control as fully set forth in the aforesaid application.

The flying machine is equipped with steering mechanism located in rear of the cabin so as to leave the body of the machine clear of anything that would increase the overhead resistance. The steering mechanism which may be of any desired construction is shown embodying a fixed vertical longitudinal plane 51 which has its lower edge substantially in line with the bottom of the cabin and which at its upper edge follows the taper of the rear end of the body. A hinged vertical rudder plane 52 is connected to the rear end of the fixed vertical plane 51 and stabilizing and elevator planes 53 and 54 are located at opposite sides of the fixed vertical plane 51 and in advance of the rudder plane 52. Any suitable operating means may of course be employed for the hinged or movable planes of the steering mechanism and while the steering mechanism is located in rear of the

cabin for the purpose explained it will be apparent that it will be effective in controlling the machine as it operates in the air operated on by the rear propellers of the power plants.

What is claimed is:

1. A flying machine of the class described, including a body substantially circular in cross section, slightly indented from a circular shape at the bottom to provide a shallow longitudinal bottom indentation of a depth materially less than that of the radius of the body, and a car or cabin extending from the body into the indentation and located partially within the body.

2. A flying machine of the class described, including a body substantially circular in cross section, slightly indented from a circular shape at the bottom to provide a shallow longitudinal bottom indentation of a width approximately equal to the radius of the body and of a depth materially less than the said radius, and a car or cabin extending from the body into the indentation and located partially within the body.

3. A flying machine of the class described, including a body substantially circular in cross section, slightly indented at the bottom to provide a shallow longitudinal indentation, and a car or cabin extending from the body into the said indentation and located partially within the latter and within the body.

4. A flying machine of the class described, including a body substantially circular in cross section and slightly indented at the bottom from a circular shape to provide a shallow longitudinal indentation presenting at the bottom of the body a transversely concave face consisting of a substantially flat central portion and curved side portions extending downwardly from the central portion, such shallow indentation being of a width approximately equal to the radius of the body and having a depth materially less than the said radius.

5. A flying machine of the class described, including a body substantially circular in cross section and slightly indented at the bottom to provide a shallow longitudinal indentation, and an interior framework comprising a central longitudinal truss or backbone extending from the top to the bottom of the body.

6. A flying machine of the class described, including a body substantially circular in cross section and tapered at the ends, said body being slightly indented at the bottom from a circular shape to form a shallow longitudinal indentation, and an interior framework extending from the top to the bottom of the body throughout the entire length of the latter and having tapered end portions fitting the tapered ends of the body.

7. A flying machine of the class described, including a body substantially circular in cross section and slightly indented at the bottom from a circular shape to form a shallow longitudinal indentation, an interior framework comprising a central longitudinal truss extending from the top to the bottom of the body throughout the entire length of the same and transverse forms of substantially circular form arranged at intervals and rigid with the truss, and a relatively long car or cabin rigid with the longitudinal truss extending into the said bottom indentation.

8. A flying machine of the class described including a body substantially circular in cross-section, and an interior framework comprising a central longitudinal truss composed of connected vertical and horizontal frame members and diagonal braces and extending from the top to the bottom of the body and transverse frames of substantially circular form rigid with the body and composed of vertical and horizontal members and diagonal cables.

9. A flying machine of the class described including a body substantially circular in cross-section, and an interior framework comprising a central longitudinal truss composed of connected vertical and horizontal frame members and diagonal braces and extending from the top to the bottom of the body, transverse substantially circular frames rigid with the truss and substantially circular ribs connected with the truss and located at intervals between the transverse frames.

10. A flying machine of the class described including a body substantially circular in cross-section, and an interior framework comprising a central longitudinal truss composed of connected vertical and horizontal frame members and diagonal braces and extending from the top to the bottom of the body, transverse circular frames rigid with the truss, substantially circular ribs connected with the truss and located at intervals between the said frames and longitudinal members connecting the ribs and the frames.

11. A flying machine of the class described including a body substantially circular in cross-section, an interior framework comprising a central longitudinal truss composed of connected vertical and horizontal frame members and diagonal braces and extending from the top to the bottom of the body throughout the length of the same, transverse circular frames rigid with the truss and arranged at intervals and circular ribs connected with the truss and arranged between the frames, and gas bags or containers located at opposite sides of the truss in two longitudinal sets or series.

12. A flying machine of the class described including a substantially cylindrical body

- having a shallow longitudinal indentation at the bottom forming a descent resisting lower face, and an interior framework comprising a central longitudinal truss extending 5 from the top to the bottom of the body and approximately circular frame connected with the truss and having bottom portions conforming to the configuration of the shallow indentation.
- 10 13. A flying machine of the class described including a body substantially circular in cross-section and having a shallow longitudinal indentation at the bottom, and an interior framework comprising a longitudinal 15 truss extending from the top to the bottom of the body throughout the length of the same and substantially circular transverse frames arranged at intervals and having arched bottom frame members located at 20 the said shallow indentation of the body.
14. A flying machine of the class described including a substantially cylindrical body provided at the bottom with a shallow longitudinal indentation a relatively long central 25 longitudinal cabin located within the shallow indentation of the bottom of the body and substantially within the radius of the said body, and a central longitudinal truss extending from the top to the bottom of the 30 body and rigidly connected with the cabin.
15. A flying machine of the class described including a body substantially circular in cross-section provided at the bottom with a shallow longitudinal indentation and a cabin 35 extending longitudinally of the body within the said indentation and located partially interiorly and partially exteriorly of the body and arranged substantially within the radius of the body.
- 40 16. A flying machine of the class described including a body substantially circular in cross-section provided at the bottom with a shallow longitudinal indentation, an interior framework having a longitudinal truss extending 45 from the top to the bottom of the body, and a cabin located at the bottom of the body and projecting therefrom at the shallow indentation and rigid with the said truss.
- 50 17. A flying machine of the class described including a substantially circular body provided at the bottom with a shallow longitudinal indentation, an interior framework having a longitudinal truss extending 55 from the top to the bottom of the body throughout the length of the same and a cabin extending within the body and also projecting exteriorly thereof at the said indentation, said cabin being incorporated in 60 the truss structure and located substantially within the radius of the body.
18. A flying machine of the class described including a body substantially circular in cross-section, an interior framework 65 having a truss extending from the top to the bottom of the body and throughout the length of the same, and a power plant casing connected to and rigid with the interior framework and arranged exteriorly of the body and communicating with the interior 70 thereof.
19. A flying machine of the class described including a body substantially circular in cross-section, said body having a shallow indentation at the bottom, an interior framework, and a power plant casing located within the shallow depression and connected to and rigid with the said framework and communicating with the interior of the body. 75
20. A flying machine of the class described including a body substantially circular in cross-section, an interior framework having a truss extending from the top to the bottom of the body, a cabin projecting at the bottom of the body and rigid with the interior framework, and power plant casings located at opposite sides of the cabin and connected with the same and with the framework and communicating with the interior of the body. 80
- 85 21. A flying machine of the class described including a body substantially circular in cross-section, an interior framework supporting the body, a cabin projecting at the bottom of the body and rigid with the framework and power plant casings located at opposite sides of the cabin and connected at their inner sides to the cabin and at their tops and outer sides with the framework and communicating with the interior of the body. 90
- 95 22. A flying machine of the class described including a body substantially circular in cross-section, said body having a shallow longitudinal indentation at the bottom, an interior framework supporting the body, a cabin rigid with the framework and projecting from the bottom of the body at the shallow indentation, and power plant 100 casings located at the sides of the cabin and connected with the same and with the framework, said cabin and power plant casings being arranged substantially within the radius of the body. 105
- 110 23. A flying machine of the class described including a body substantially circular in cross-section provided with a shallow longitudinal indentation, an interior framework, a cabin projecting from the bottom of the body within the shallow indentation and connected with the framework, and steering mechanism located in rear of the cabin and including a fixed vertical plane and a hinged rudder plane, the rear end of the body being tapered and the said planes being tapered and fitting the tapered rear end of the body. 115
- 120 24. A flying machine of the class described including a body substantially circular in cross-section, said body having a shallow longitudinal indentation at the bottom, an interior framework, a cabin projecting from the bottom of the body within the shallow indentation and connected with the framework, and steering mechanism located in rear of the cabin and including a fixed vertical plane and a hinged rudder plane, the rear end of the body being tapered and fitting the tapered rear end of the body. 125
- 130

cular in cross-section, interior framework including a truss extending from the top to the bottom of the body and throughout the length of the same, said body and truss 5 having tapered rear portions, a cabin extending longitudinally of the body at the bottom and connected with the interior framework and steering mechanism including a vertical plane located in rear of the 10 cabin and arranged beneath and connected with the said truss and tapered to fit the tapered rear end of the body.

25. A flying machine of the class described including a substantially circular body, an interior framework having a central, longitudinal truss and provided with a relatively narrow vertical longitudinal passage defined by the truss and having walls connected therewith and stiffening the 20 body.

26. A flying machine of the class described including a body substantially circular in cross-section, an interior framework having a longitudinal truss extending from the top to the bottom of the body, 25 said framework being also provided with a relatively narrow longitudinal passage and having lateral extensions, a cabin projecting from the bottom of the body and 30 connecting with the interior framework, and power plant casings located at opposite sides of the cabin and having tubular portions connected with the lateral extensions of the 35 said passage.

27. A flying machine of the class described, including a body substantially circular in cross-section and slightly indented at the bottom to form a shallow longitudinal indentation, an interior longitudinal truss, 40 a cabin rigid with the truss and extending therefrom into the indentation, and landing gear connected with the truss and arranged exteriorly of the body.

28. A flying machine of the class described, including a body substantially circular in cross-section and indented at the bottom from a circular shape to provide a shallow longitudinal indentation, an interior framework having a longitudinal truss extending from the top to the bottom of the 45 body, a cabin connected with the interior framework and extending into the indentation, and landing gear arranged exteriorly of the body at the said indentation and connected with the said framework. 50

29. A flying machine of the class described, including a substantially circular body in cross-section and slightly indented at the bottom to provide a shallow bottom longitudinal indentation, an interior framework, a cabin extending longitudinally of the bottom of the body in the said indentation and connected with the said framework, power plant casings located at opposite 60 sides of the cabin, and landing gear located at opposite sides of the body and connected with the same and with the power plant cas- 65 ing.

30. A flying machine of the class described including a substantially cylindrical body, an interior framework having a central, vertical, longitudinal truss extending from the top to the bottom of the body and composed of connected vertical and horizontal frame members and diagonal braces, 70 a cabin extending longitudinally of the bottom of the body and connected with the framework, power plant casings located at opposite sides of the bottom, and landing gear located at opposite sides of the body 75 and connected with the same and with the power plant casings. 80

In testimony whereof I affix my signature.

THOMAS MILTON FINLEY.
